CATHODE FOR MAGNETRON DEVICES

Ilia Emmanuel Mouroutseff, Montclair, and John Hamley Findlay, Upper Montclair, N. J., assignors to Westinghouse Electric Corporation, East Pittsburgh, Pa., a corporation of Pennsylvania

Application December 24, 1941, Serial No. 424,316

7 Claims. (Cl. 250—27.5)

This invention relates to cathodes for electron discharge devices and more particularly to oxide coated cathodes for use in electron discharge devices of the magnetron type.

Electron discharge devices of the magnetron type are employed in the art for generating or sustaining electrical oscillations of very high frequency. Such devices usually contain an anode of generally cylindrical shape with an elongated electron emitting cathode axially sustained therein with both elements enclosed within an evacuated glass envelope. It is found in such devices that the portion centrally of the length of the cathode element of the tube reaches a higher equilibrium temperature than the end portions of the length of said cathode, to which several reasons may be ascribed. One reason is that this central portion of the cathode is subjected to more severe electron bombardment than the end portions. Another reason is that the ends are more favorably situated for radiation. Yet another reason is that less bombardment occurs at the end portions than at the central portion. Bombardment results in the loss and destruction of the thermionically active material on the surface of the cathode. Also the higher temperature of the central portion of the cathode results in evaporation of the active material, and in either event the active material lost from the cathode is in greater part found to be deposited on the inner concave face of the anode. This deposit on the anode materially interferes with the operating characteristics of the magnetron device and shortens the operating life and efficiency of the device.

One of the objects of the present invention is to eliminate this defect in an electron discharge device of the magnetron type thereby to increase the operating life and efficiency of magnetron devices.

Another object is to provide an improved electron emitting cathode for a magnetron device.

Still another object is to provide an oxide coated cathode for an electron discharge device of the magnetron type which is not deleteriously affected by electron bombardment.

Other objects and advantages will be apparent as the invention is more fully hereinafter disclosed.

In accordance with these objects, we have discovered that by locating the thermionically active material adjacent the ends of the cathode leaving the intervening or central area of the cathode bare and exposed to electron bombardment, the defect hereinabove noted, not only is eliminated

but that the operating characteristics of the device are stabilized and remain substantially constant for relatively prolonged periods of time as compared with devices provided with cathodes that are thermionically active over substantially their entire length. We have found that by locating the thermionically active material on the cathode surface at a point remote from the area of intense electron bombardment and within the area wherein the temperature of the cathode remains substantially constant, the amount of such material on the cathode may be reduced materially to an amount required to produce a sufficient quantity of electrons to initiate operation of the device and that the secondary emission of the uncoated area produced by electron bombardment plus the electron emissivity of the electron emitting material on the cathode end portions is ample for continued operation of the device; and 10 we have further found that by eliminating the evaporation of the electron emitting material onto the anode by so locating the electron emitting material on the cooler end portions of the cathode the operating characteristics of the device remain constant over a prolonged period of time as compared to prior art devices.

In accordance with these discoveries we have devised the electron emissive cathode of the type illustrated in the drawing for use in magnetron devices.

Referring to the drawing:

Fig. 1 is a sectional view of a magnetron device showing the essential elements thereof;

Fig. 2 is a cross-sectional view of the same 35 along plane 2—2 of Fig. 1;

Fig. 3 is a sectional view of the improved electron emissive cathode of the present invention;

Fig. 4 is a cross-sectional view of the same 40 along plane 4—4 of Fig. 3; and

Fig. 5 is a contemplated modification of the present invention.

As indicated in the drawing, a magnetron device comprises a split anode A—A surrounding in the present instance an indirectly heated tubular cathode C sustained in concentric spaced relation within evacuated glass envelope G by means of lead-in support wires a—a and c—c, respectively, passing through press P of the envelope G. Magnetic coil M is provided to produce a magnetic field of the desired character within the device.

In accordance with the present invention, cathode C is shown as comprising an elongated tubular metal base member 19 provided with a heater element 11 concentrically disposed there- 55 in as is customary in the art. A surface coating

E—E' of thermionically active material is present on the outer surface of each end portion of the base 10, extending inwardly in each instance from the end portion towards the center a distance at least sufficient to provide enough emission for energization and actuation of the device. The active material is therefore insufficient in extent to be located upon the central area of the tube subjected during operation to intense electron bombardment with consequent high temperature and evaporation.

It is believed apparent that the amount of thermionically active material E—E' deposited on the end portions of base 10 of the cathode C may vary widely without essential departure from the present invention, depending upon the nature of material employed and upon the field of use for which the device is designed. In general, the object is to locate the thermionically active material E—E' on the area of the cathode surface which in the normal operation of the device has lowest temperature and is subjected to the least electron bombardment. This area obviously varies with respect to the tube design, such as anode length and anode-cathode spacing and for devices where the electron bombardment during normal operation may extend over the greater portion of the length of the cathode enclosed by the anode. It is contemplated that the cathode C may be elongated at least sufficiently to provide an area at each end that is beyond the area of disruptive electron bombardment upon which the electron emitting material E—E' may be located.

Irrespective of the fact that the electron emissive material E—E' is limited to the area of the base 10 which is remote from the area of intense electron bombardment, and at a temperature substantially below the vaporization temperature of the electron emitting constituent thereof, the exposed or uncoated area of the base 10 still functions under the influence of electron bombardment as an emitter of secondary electrons. Accordingly, base 10 may be comprised of any one of a plurality of metals and alloys heretofore known in the art to be of utility as an emitter of secondary electrons under electron bombardment. Preferably, base 10 is comprised of substantially pure nickel, but alternatively may be comprised of molybdenum or of one of the various nickel alloys heretofore found satisfactory as a base metal for thermionically active oxide coatings for such cathodes.

Within the contemplation of the present invention also is the provision of a cathode consisting of a tubular base 20 comprised of a metal or metal alloy highly reactive as an emitter of secondary electrons under electron bombardment but not necessarily suitable for use as a base for electron emitting material E—E' wherein material E—E' is located on sleeve members 21—21' comprised of material suitable for use as a base for electron emitting material E—E' and adapted to be slipped onto the ends of tubular base 20 substantially as indicated in Fig. 5.

Having hereinabove described the present invention generically and specifically and described and illustrated one specific embodiment thereof, and for simplicity having omitted herefrom further illustration and description of other modifications and departures from the precise showing herein, but which might have been included in substitution for or in addition to the selected showing, applicants do not disclaim any such modifications and departures as may fall within the scope of the following claims.

We claim:

1. A magnetron device having a magnet establishing a concentrated field, an anode having an electron-receiving face in said field and an envelope enclosing the electron-receiving face of said anode, an electron emitting cathode within said envelope and opposed to said electron-receiving face of the anode, said cathode consisting of an elongated metal base member having the thermionically active surface area thereof restricted to the area adjacent each end of the base member, all active areas of the cathode being situated in the said concentrated field of the magnet.
- 15 2. A magnetron device having a magnet establishing a concentrated field, an anode having an electron-receiving face in said field and an envelope enclosing the electron-receiving face of said anode, an electron emitting cathode within said envelope and opposed to said electron-receiving face of the anode, said cathode consisting of an elongated metal base member having the thermionically active surface area thereof restricted to the area adjacent each end of the base member and consisting of material resistant to evaporating under electron bombardment, all active areas of the cathode being situated in the said concentrated field of the magnet.
- 20 3. A magnetron device having a magnet establishing a concentrated field, an anode having an electron-receiving face in said field and an envelope enclosing the electron-receiving face of said anode, an electron emitting cathode within said envelope and opposed to said electron-receiving face of the anode, said cathode consisting of an elongated metal base member having the thermionically active surface area thereof restricted to the area adjacent each end of the base member, said base member in the area intermediate said thermionically active end areas consisting of material of relatively high secondary emissivity under electron bombardment, all active areas of the cathode being situated in the said concentrated field of the magnet.
- 25 4. An electron emitting cathode consisting of an elongated metal base member having the thermionically active surface area thereof restricted to the area adjacent each end of the base member, said base member comprising an elongated metal tube consisting of substantially pure nickel and the said thermionically active surface area adjacent each end of the tube comprising a thermionically active oxide coating, said oxide coating being limited to the area of said tube surface beyond the area of intense electron bombardment and within the end areas of the said cathode.
- 30 5. A cathode element consisting of an elongated tubular base consisting superficially in the center area thereof of material of relatively good secondary electron emissivity under electron bombardment and at each end thereof superficially of material of relatively high primary electron emissivity, and means interiorly of said tubular base member to heat the end areas of the said tubular base member to the temperature of primary electron emissivity.
- 35 6. A cathode element comprised of an elongated tubular metal base member consisting of nickel, a thermionically active oxide coating disposed on the surface of said base member within the area adjacent each tubular end remote from electron bombardment during operation, and heater means disposed within the said tubular member to heat the end portions of the said tubu-

lar member to the temperature of electron emissivity of said oxide coating thereon.

7. A magnetron device comprising an envelope, an anode in said envelope, a magnet presenting a concentrated field within said anode, an electron-emitting cathode in said field and anode, said cathode consisting of an elongated metal base member having the thermionically active surface area thereof restricted to the area adjacent each end of the base member, said base member comprising an elongated metal tube consisting of substantially pure nickel and the said thermionically active surface area adjacent each end of the tube

comprising a thermionically active oxide coating, said oxide coating being limited to the area of said tube surface beyond the area of intense electron bombardment during operation of said device and within the end areas of the said cathode, and means within said envelope for thereby heating the end portions of the tube and thermionically active coating on the end areas thereof to the temperature of electron emissivity of said coating.

ILIA EMMANUEL MOUROMTSEFF.
JOHN HAMLEY FINDLAY.
